N. BAUMANN.

Flour Bolt.

No. 18,179.

Patented Sept. 15, 1857.

UNITED STATES PATENT OFFICE.

N. BAUMANN, OF ELMORE, ILLINOIS.

FLOUR-BOLT.

Specification of Letters Patent No. 18,179, dated September 15, 1857.

To all whom it may concern:

- Be it known that I, N. BAUMANN, of Elmore, in the county of Peoria and State of Illinois, have invented a new and Improved 5 Flour-Bolt; and I do hereby declare that the following is a full, clear, and exact description of the same, reference being had to the annexed drawings, making part of this specification, in which—
- 10 Figure 1, is a transverse vertical section of my improvement, (x) (x) in Fig. 2, showing the plane of section. Fig. 2, is a longitudinal section of the same; (y) (y) Fig. 1, indicating the plane of section.
- 15 Similar letters of reference indicate corresponding parts in both figures.
- My invention consists in the employment or use of a stationary shell or case which is formed of metal or wood and of a peculiar 20 shape, the shell or case having a frame covered with bolting cloth attached to one side of it. Within the case or shell is placed a rotating shaft, having beaters attached; and the whole is so arranged that the rotation of 25 the beaters in connection with the form of the shell or case will cause the flour to be thoroughly detached from the bran and a perfect separation of the bran and flour effected.
- 30 To enable those skilled in the art to fully understand and construct my invention, I will proceed to describe it.
- A represents a box or chest of rectangular form, and B represents a shell or case permanently secured therein; the said shell is secured longitudinally within the box A, but somewhat inclined as shown in Fig. 2.
- 35 The shell or case B transversely is formed of two curves (a) (b) which are so shaped and connected together as to form a recess (c), a pendant projection (d) being in front of the recess, between the said recess and the front and open side of the shell. The front side of the shell or case has a frame (e) secured to it, and this frame is covered by a bolting cloth (f).
- 40 The depressed or lower end of the shell or case B is provided with a spout (g) which passes through the end of the box or chest, and the elevated end at its upper side has an aperture (h) made in it.
- 45 Within the shell or case B, a shaft C is placed longitudinally, the journals of said shaft being fitted in suitable bearings at the ends of the box or chest. This shaft is provided with a cone of pulleys (i) at one end;
- and a series of arms (j) are secured upon the shaft C; said arms having flat plates or beaters (k) secured to their outer ends. The plates or beaters have a tangential position 50 relatively with the shaft C, and three beaters are shown in the drawings but more or less may be used. The beaters (k) are not parallel with the shaft C, but are placed somewhat spirally with it, as seen in Fig. 2; 55 and the edges of the beaters do not quite touch the surface of the curved portion (a) of the shell or case.
- The operation is as follows:—The ground grain passes into the elevated end of the 60 shell or case B, through the aperture (h) and the shaft C is rotated in the direction indicated by the arrow Fig. 1, with a speed of about 200 or 250 revolutions per minute. As the shaft C rotates, the beaters (k) will 65 throw the ground grain into the recess (c) with considerable force; the ledge (d) serving to arrest it, and the concussion or jar to which the ground grain is subjected will cause the flour to be detached from the bran. 70 The bran and flour are both thrown against the bolting cloth (a) by the beaters (k), the flour passing through the bolting cloth into the chest or box A, while the bran is fed toward the spout (g) by the spiral form of 75 the plates or beaters (k).
- 75 My improved bolt may be cheaply constructed, and as the ground grain is thrown around within the shell or case, no cooler is required, as the ground grain is scattered or 80 spread out and brought in contact with the air so that it is quickly cooled. This is an important feature in the invention as the bolt may receive the ground grain direct from the stones. Another advantage is that 85 the frame (e) may be readily detached from the shell or case, and bolting cloths of different degrees of fineness attached to said shell or case, so that flour of any required quality may be obtained, as desired. My 90 improvement therefore will be valuable in grist mills, for some farmers desire a small quantity of flour from a given quantity of grain, while others desire a larger quantity; the smaller the quantity of flour obtained, 95 the better of course will be the quality. Wet or damp grain may also be bolted by my improvement, and in case the bolting cloth becomes clogged, it may be readily detached from the shell or case B, and cleaned.
- 100 Thus it will be seen that my improved bolt is simple in construction, is not expensive to 105

build, is effective in its operation, and possesses advantages as regards the varying qualities of flour that may be obtained by adjusting the cloth and regulating the speed 5 of the beaters, and also in cooling and drying the ground grain.

I am aware that beaters placed both parallel and spirally with their shaft have been used for similar purposes; and I therefore 10 do not claim said beaters separately; but

Having thus described my invention, what

I claim as new, and desire to secure by Letters Patent is:—

The shell or case *B*, curved or formed as shown, in combination with the rotating 15 beaters (*k*) and frame (*e*) with bolting cloth (*f*) attached; the whole being arranged as shown for the purpose set forth.

NEPOMUK BAUMANN.
